C. KRÄMER

VAPOR ELECTRIC DEVICE

Filed June 20, 1923

Inventor:
Christian Krämer:
by *Alexander S. Zaitz*
His Attorney.

UNITED STATES PATENT OFFICE.

CHRISTIAN KRÄMER, OF PANKOW, GERMANY, ASSIGNOR TO GENERAL ELECTRIC COMPANY, A CORPORATION OF NEW YORK.

VAPOR ELECTRIC DEVICE.

Application filed June 20, 1923, Serial No. 646,538, and in Germany July 27, 1922.

The present invention relates to vapor electric devices, particularly mercury arc rectifiers of large power, and it is the object of my invention to provide means for preventing deleterious reverse arcing and similar disturbances in these devices.

In accordance with my invention I have provided a new form of anode for vapor electric devices which is provided with a large number of distinct projections.

The accompanying drawing shows in section a rectifier containing an anode embodying my invention.

One of the causes of reverse discharges in rectifiers that is, discharges having a polarity opposite to the rectifier current, is the concentration of the discharge at an accidental point or protuberance on the anode surface, for example, a fusion globule on the anode surface. Hereby this part of the anode becomes very highly heated thereby giving rise to reverse arcing. Formerly, the anode surfaces were carefully rounded, and in some cases even highly polished and plated with nickel or precious metal.

In contrast to this procedure I have provided the anode with numerous distinct points or protuberances, to prevent a concentration of the arc. One embodiment of my invention is shown in the drawing. The rectifier illustrated comprises as usual a con-

tainer 1, in which there is provided a cathode, 2, and an anode 3. The side branch, or starting anode 4, has nothing to do with my invention as any suitable starting means 35 may be used.

The anode 3, which may consist of graphite, tungsten, or other suitable material, is provided with numerous sharp corners and edges by cross riffling the same as indicated. 40 By this means there are present instead of an accidental single point or few points, a multitude of small projections or knurls distributed over the surface of the anode so that a dangerous concentration of current at 45 an isolated point is avoided. Experience has shown that the danger of reverse arcing is materially reduced in devices containing the described form of anode.

What I claim as new and desire to secure 50 by Letters Patent of the United States, is:

1. An anode for electric discharge devices, said anode being provided with a knurled surface.
2. An anode for vapor electric devices 55 which has a surface provided with cross riffling, thereby producing a plurality of sharp corners.

In witness whereof, I have hereunto set my hand this 24th day of May, 1923.

CHRISTIAN KRÄMER.
